UNITED STATES PATENT OFFICE

WILLIAM J. PARKER, OF WATERBURY, CONNECTICUT

NAIL HOLDER FOR SHINGLES

Application filed February 8, 1929. Serial No. 338,551.

This invention relates to a nail holder for shingles, and particularly, to an improved device which will automatically move the nail to correct position to be driven as the shingle is moved to its correct position on the roof.

The object of the invention is to provide a nail holder for any kind of shingle, but particularly, for artificial shingles, the structure being such that the nail is automatically held in the correct position for driving when the shingle has been correctly positioned.

Another object, more specifically, is to provide a nail holder for asbestos shingles, slate shingles and other artificial shingles, the holding means including a swingable member for normally holding the nail flatwise against the shingle and automatically guiding the nail to a correct driving position when the shingle is moved to a position near the vertical, whereby the workman can hold the shingle in correct position with one hand and use a hammer with the other hand.

In the accompanying drawings,—
Figure 1 is a substantially top plan view of part of the roof supplied with shingles having nail holders embodying the invention;

Figure 2 is a sectional view through Figure 1 on the line 2—2, the same being on an enlarged scale;

Figure 3 is an enlarged fragmentary plan view of part of a shingle with a holder shown in a folded position applied thereto;

Figure 4 is a sectional view through the Figure 3 approximately on the line 4—4, the same being on a somewhat enlarged scale;

Figure 5 is an enlarged fragmentary sectional view through Figure 1 approximately on the line 5—5;

Figure 6 is a view similar to Figure 1 but showing a different form of shingle with a different means for fastening the nail holder to the shingle;

Figure 7 is a plan view of one of the shingles shown in Figure 6, the same being on an enlarged scale and illustrating the arrangement of the nail holder used in Figure 6;

Figure 8 is a sectional view through Figure 9 on the line 8—8;

Figure 9 is a fragmentary sectional view through Figure 6 on the line 9—9;

Figure 10 is a fragmentary sectional view through Figure 6 on the line 10—10.

Referring to the accompanying drawings by numerals, 1 indicates an artificial shingle, as for instance, an asphalt shingle of a well-known make. In placing these shingles on a steep roof it is necessary to hold the shingle in place and to hold the nail or nails in place while a workman drives the nail to its final position. On a cold day it is very difficult to hold the hammer, the shingle and the nail. In the present instance, means have been presented for automatically holding the nail in position so that the workman may hold the shingle in one hand and may use the hammer with the other hand. As shown in the drawings each shingle has been provided with one nail, though, if desired, two or more nails could be used without departing from the spirit of the invention. The various nails 2 also may be of any desired type but preferably with a comparatively flat head so that when the nail is lying substantially parallel with the shingle, as shown in Figure 4, it will not offer much of a projection, so that other shingles may be stacked thereon. The nail 3 is threaded through apertures 4 and 5 of a supporting plate 6, said supporting plate being bent at 7 to provide a base 8 which is secured to the shingle 1 in any desired manner, as for instance, a staple 9. The plate 6 is provided with a right-angle portion 10 which acts as a base for holding the plate substantially at right angles to shingle 1 when the nail is ready to be driven. Preferably, the holding structure which consists of the base 8, plate 6 and brace 10 is made from paper, though it could be made from some other material. When the parts are folded they assume the position shown in Figs. 3 and 4. When in this position the brace 10 is fitted flatwise against the plates 6, but by reason of the resiliency of the paper and other material used the brace 10 swings outwardly to an almost right-angle position when any weight resting thereon is removed. When the shingle is moved from a horizontal position to a decided angle, as shown in Fig-

ure 5, the weight of the nail 3 will cause the plate 6 with its brace 10 to swing away from base 8 under the action of gravity. If it were not for the brace 10 plate 6 would swing completely over until it is laid flatwise against the shingle below base 8, but the brace 10 prevents this action and stops the movement of the nail when it reaches substantially the position shown in Fig. 5.

10 The workman may then strike the nail with a hammer and drive the nail in to any desired extent. During the driving operation the paper plate 6 and brace 10 are crushed, but this is of no consequence, as these members have already performed their function.

15 In Figs. 6 to 10 inclusive will be seen a modified form of invention wherein the same inventive idea is disclosed but with the parts applied to stiff shingles 11. These shingles 20 may be made from slate, cement, asbestos, tile or other material. Each of these shingles is shown provided with three apertures 12, and a holder 13 may be associated with each aperture 12, though preferably a holder 25 is associated with two apertures in each shingle, namely, aperture 12' and 12''. When applying the invention to shingles of this type the base 8 is cemented by tar, cement or some other form of cement 8' to the shingle so that 30 when the shingle is moved toward a vertical position the nail will swing to a substantially right-angle position, and in fact, will swing to such a position that the lower end of the nail will actually project into the aperture 12' 35 or 12'', as the case may be. It is understood that the nails may be of any desired length and shape but preferably with a comparatively narrow head, so that a number of shingles may be stacked. This construction, 40 when used on stiff shingles as shown in Fig. 6, is very desirable, as it in effect prevents breakage of shingles, as the nail is always in correct position, and consequently, may be more easily driven to its final position 45 without breaking the shingle. Adjacent the holes or apertures 12' and 12'' are notches 14 and 15, which register with similar notches in adjacent shingles. These notches accommodate the storm nail 16 which is preferably 50 of copper, though it could be made from some other comparatively soft metal. The holder 16' is identical with the holder 13. Instead of causing the nail to fit into an aperture similar to apertures 12' and 12'', the holder 55 supports the nail with the head 17 near the shingle so that when the holder swings outwardly the head will move into a depression 18 formed in the shingle. This will leave the nail 16 standing upright, so that adjacent 60 shingles may be slid to a point in contact therewith in order that the nail will project into apertures of adjacent shingles, as clearly shown in Figs. 6 and 10. When this takes place the parts will appear as shown in Fig. 65 10 and at the proper time the workman

strikes the projecting part of the nail 16 so as to bend the same over against one of the adjacent shingles. This will provide a lock to prevent this part of the shingle from leaving the next adjacent shingle, while the 70 nails in holes 12' and 12'' will rigidly secure the shingle to the supporting part of the roof. As shown in Figure 8, each of the holes, 12, 12' and 12'' is made as shown in Figure 8, namely, with a countersunk portion 19 merging into the aperture, whereby the countersunk portion accommodates all or most of the head of the nail. This presents a smooth surface over which the next adjacent shingle extends. It will be understood 75 that applicant's invention does not include the detail construction of the shingle except for the countersunk portion 18 or the counter-sunk portion 19.

What I claim is:—

1. A nail holder for shingles, comprising a supporting structure for a nail having a portion swingable from one position to the other, and means for holding said supporting structure substantially permanently on the 90 shingle.

2. A nail holder for shingles, comprising a plate formed with apertures for receiving a nail, a brace connected with said plate and a base connected with said plate, said brace 95 acting to hold the plate substantially at right angles to the base when in operative position.

3. A nail holder for shingles, comprising a base and means for securing the base flatwise against a shingle, an apertured plate normally lying flatwise against said base and hingedly connected thereto at one edge thereof, said apertures being adapted to accommodate a nail, and a brace hingedly connected to one edge of said plate, the axis of the hinge connection last-mentioned being at 100 right angles to the hinge connection first-mentioned.

4. A nail holder for shingles, comprising a base, means for fastening the base flatwise against a shingle, said base having an integral extension forming a holding plate, said base at the juncture with said extension being bent so that the plate normally lies flat against the base, said plate having a pair of aligned apertures for receiving a nail, whereby when said shingle is held substantially vertically said plate will swing away from said base, said plate having a bent portion acting as a brace and automatically moving to a right-angle position from the plate when released, whereby as the plate swings away from the base said brace will check the swinging movement when the nail has reached a substantially right-angle position to the 115 shingle.

5. A nail holder for shingles, comprising foldable means adapted to be connected with a shingle, said foldable means including an apertured member for holding a nail, and a 130

brace extending at right angles thereto, said brace being positioned so that one edge will strike the shingle and hold the nail at right angles to the shingle, said holding means being readily collapsible so that when said nail is driven into the shingle the holding means will not interfere.

6. A nail holder for shingles, comprising a base of paper, means adapted to pierce said base for securing the base to a shingle, said base of paper having an extension acting as a holding plate, said holding plate being normally bent so as to lie flatwise against said base but capable of being swung to a position at right angles to the base, said plate having apertures for receiving a nail, said plate of paper having an extension or flange at one edge normally folded against the plate but by reason of the resiliency of the material automatically swinging to a position at right angles to the plate when released, whereby it may act as a brace for holding the nail at substantially right angles to the shingle when the shingle has been moved to a position greater than a 45° angle.
